UNITED STATES PATENT OFFICE.

CHARLES T. THOMPSON, OF PHILADELPHIA, PENNSYLVANIA.

END-SUPPORT FOR RODS.

1,227,019.

Specification of Letters Patent.

Patented May 22, 1917.

Application filed June 14, 1916. Serial No. 103,623.

To all whom it may concern:

Be it known that I, CHARLES T. THOMPSON, of Philadelphia, in the county of Philadelphia and State of Pennsylvania, have invented certain new and useful Improvements in End-Supports for Rods, of which the following is a specification, reference being had to the accompanying drawings.

My invention relates to an end-support for rods (such as curtain rods), and comprises a slotted socket piece within which the end of the rod is received, and a slotted cap piece rotating eccentrically with relation to the socket piece, the eccentric relation of the cap piece to the socket piece producing a clamping action, by means of which the end of the rod may be firmly clamped in its supporting socket piece.

In the accompanying drawings, Figure I, 20 is a partial sectional view, illustrating my invention as used to support the ends of a curtain rod.

Figs. II, and III, are views of my device, showing the cap piece in two different positions.

Fig. IV, is a perspective view of the socket piece, and

Fig. V, a similar view of the cap piece.

The socket piece (see Fig. IV) comprises 30 a base 1, which is centrally pierced in order to permit it to be affixed to its upright support by the screw 2. Integral with the base is the collar 3, terminating in the flange 4. Both the collar and its flange are provided 35 with a slot 5, on the upper side in order that the end of the rod may be properly inserted into the socket formed by the interior of the collar.

The cap piece (see Fig. V) consists of a 40 disk 6, provided with an overhanging flange 7. The disk is centrally pierced and both the disk and its overhanging flange are provided with a slot 9, as shown in the drawings. The overhanging flange 7, of the cap 45 piece embraces flange 4, of the socket piece, so that the cap piece rotates thereon, but the formation of this overhanging flange is such that the rotation thus provided is an eccentric one in relation to the socket piece.

This is best illustrated by reference to Fig. 50 II, where the dotted line 8, represents the contacting surfaces of the outer edge of the flange 4, and the inner surface of the overhanging flange 7.

In use the socket piece is affixed to the 55 upright support as shown in Fig. I, with its slotted edge uppermost. If the slot of the cap piece be rotated into coincidence with the slot of the socket piece, as shown on the left hand of Fig. I and in Fig. II, the end 60 of the rod is readily inserted within the socket from above. Thereupon the cap piece is rotated upon the socket piece. The eccentricity of their relation brings increasing pressure to bear upon the rod contained 65 within the socket which reaches its maximum when the cap piece has been reversed in position, as shown on the right hand of Fig. I and in Fig. III. The wedging action accomplished by this rotation not 70 only clamps the rod firmly in position so as to prevent rattling, but serves to hold the cap piece from unintended rotation thereafter.

Having thus described my invention, I 75 claim:

1. An end-support for a rod, comprising a socket piece with a flanged socket slotted upon one side, and a similarly slotted pierced cap piece embracing the flange of the socket 80 piece and rotating eccentrically thereupon.

2. An end-support for a rod, comprising a stationary socket piece having a slot adapted to engage the rod to be supported; a cap piece rotatably mounted on said socket 85 piece, also having a slot adapted to engage said rod, said cap piece being eccentrically mounted on said socket piece, so that the rotation of the cap piece causes the edges of the slot to exert a binding action on said 90 rod.

3. An end-support for a curtain rod, composed of two members, namely, a socket piece, provided with the socket 2, and the flange 4, both being slotted upon one side, 95 and a centrally pierced cap piece comprising the disk 6, and the overhanging flange 7, both being similarly slotted upon one side,

the overhanging flange of the cap piece embracing the flange 4, of the socket piece, the contacting edges of these flanges being in eccentric relation in the axis of the socket piece, whereby a binding action is obtained by the rotation of said cap piece.

In testimony whereof, I have hereunto

signed my name at Philadelphia, Pennsylvania, this sixth day of June 1916.

CHARLES T. THOMPSON.
